SHOULDER PAD AND METHOD OF MAKING
SAME

William H. Hawkins, Brooklyn, N. Y., and
Maurice Selditz, Stamford, Conn., assignors to
Freydberg Bros., Inc., Stamford, Conn., a cor-
poration of New York

Application December 9, 1937, Serial No. 178,864

17 Claims. (Cl. 2—267)

This invention relates to shoulder pads as well as the method of making the same, and more particularly to shoulder pads such as used by tailors and clothing manufacturers in building up the shoulders of coats.

The nature and objects of the invention will become clear from the following description, appended claims, and accompanying drawing forming a part of this specification and in which:

10 Figure 1 is a top plan view of a shoulder pad blank made in accordance with this invention;

Figure 2 is a section of the shoulder pad blank at stage in the process of making the same;

15 Figure 3 is a perspective view of a shoulder pad embodying the principles of this invention;

Figure 4 is a section of another embodiment of a shoulder pad constituting the instant invention; and

20 Figure 5 is a section of another embodiment of a shoulder pad embodying the principles of this invention.

To meet the requirements and give the best results in use, shoulder pads of the type to which the instant invention relates should be relatively thick at the central zone along one edge and then taper off gradually and uniformly to the other or outer edge which should be relatively thin. Thus, the shoulder pad constituting one phase of the instant invention is relatively thick at the 25 central zone along one edge and gradually and uniformly tapers off therefrom to its outer or other edge which is relatively thin.

Generally, the shoulder pad of the instant invention comprises a filler preferably shaped to the desired form and provided with facings on the top and bottom thereof. In the preferred form, the filler is formed of a mass of fibers which, in order to give the pad its desired form and shape, is so formed that it is relatively thick at the 30 central zone along one edge and then tapers off gradually and uniformly from said thickened portion towards its other or outer edge to form a relatively thin edge. The facings are coextensive and each of them is of such dimensions that it 35 projects the thin edge of the mass of fibers, with the consequence that the projecting portions thereof are superposed and in contractual relationship. Due to the method employed in the production of the pads, and more fully explained 40 hereafter, the superposed portions of the facings which are in contractual relationship are substantially integrally united to each other, as by being 45 felted together. The facings are also united to at least the surface of the fibers contracting 50 therewith.

In preparing the aforementioned shoulder pad, a shoulder pad blank is first prepared, and such blank transversely severed, whereby a pair of complementary shoulder pads is produced. In accordance with one embodiment of this invention, 5 individual cotton or wool fibers are showered under air pressure or suction upon a foraminous support, such as a wire screen, preferably rotating, so that the separate fibers do not extend in any one direction but extend in all directions and become interconnected with each other to form a connected mass wherein the fibers in the central zone of the blank are more numerous and more densely compacted than those at the outer edge of the blank, the said density gradually decreasing outwardly, and wherein the upper surface of the blank is rounded or convex and tapers off smoothly and uniformly in all directions from its center towards its outer edge which is relatively thin. The precise manner of producing 10 this predetermined shaped mass of fibers is described in applications Serial Nos. 66,208 and 15 170,008.

After the fibers have been formed into the shaped mass as described, the mass may be filled 25 with entrapped air and therefore may be somewhat expanded or puffed. When this condition exists, the blank is compressed in a longitudinal direction to force out the entrapped air. The resulting shaped mass of fibers is of sufficient 30 strength to permit handling and constitutes the filler of the shoulder pad blank and the final pad. The shaped mass of fibers is processed so that it is provided on the top and bottom surfaces thereof with facings.

35 In one embodiment of the invention, a layer of a material containing feltable fibers and in the form of a loose bat, such as is secured after garnetting or carding, is disposed on the top and bottom surfaces of the shaped mass of fibers. The 40 layers of feltable fibers are substantially coextensive and each is of a size such that the edge thereof projects beyond the thin edge of the shaped mass of the fibers, thereby providing the blank with a marginal portion adjacent its edge and in which the layers containing the feltable fibers are in superposed contractual relationship. When the blank has been assembled as just described, it is subjected to a felting operation 45 whereby the layers containing the feltable fibers are felted in situ on the shaped mass of fibers. Due to this mode of operation, those portions of the layers of feltable fibers which are in superposed contractual relationship are substantially 50 integrally united by being felted together. Also, 55

due to the fact that the felting operation is carried out in situ on the predetermined shaped mass, the inner surfaces of the layers contained the feltable fibers are substantially united to the outer surface of the shaped mass of fibers.

5 In producing the shoulder pad blank, a pair of oppositely disposed notches are provided in the edge thereof. After the blank has been produced as above described, it is severed along a line connecting the centers of the notches. The resulting two halves constitute a pair of complimentary shaped shoulder pads.

10 The shoulder pad blank may be made of any desired shape and size depending on the requirements of the trade.

15 Though in the preferred embodiment of the invention the fillers are formed by showering cotton or wool fibers under air pressure or suction upon a rotating foraminous support, they 20 may be produced or built up in any desired manner.

25 If desired, instead of forming the filler of cotton or wool fibers, it may be formed of a composition containing feltable fibers similar to that which constitutes the facing. Thus, the blank contains fibers having the felting characteristics throughout. When the blank contains feltable fibers throughout, it may be subjected to the felting operation so that it is felted throughout. Alternately, the blank may be subjected to the felting operation for such a period of time 30 so that the surfaces thereof are only felted to constitute felted facings. By varying the time of the felting operation, the blank may be felted to any desired degree, namely, the blank may be felted throughout or have only its facings felted. By varying the degree of felting, pads having different degrees of hardness may be secured.

35 A pad in which the filler-containing fibers 40 having the felting characteristics and irrespective of the degree of felting thereof will be harder than that in which the filler is formed of cotton or wool. If a pad is desired of a hardness which is intermediate that obtained when cotton or wool 45 fibers and feltable fibers are used, a mixture of cotton fibers and feltable fibers may be used. A satisfactory fiber mixture is one containing approximately 90% cotton fibers and 10% feltable fibers.

50 It is within the scope of this invention to make the filler of a mixture of different fibers felted throughout or not as desired.

55 As the feltable fiber which constitutes the facing or the filler when so desired, any fibers which possess the felting characteristic may be used. In the preferred form of the invention, hatters' waste constitutes the feltable fibers. If desired, the hatters waste may have in it carbonized or depitched noils or Texas wool or any other wools 60 that have felting characteristics. Still further, if desired, a little China cotton or other adulterant may be incorporated in the mass.

65 The fibers having felting characteristics are garnetted or carded and formed into loose bats. From these loose bats discs of the desired dimensions are cut or stamped and these discs are applied to the shaped fillers and result in the facings of the pads.

70 The felting operation is effected by appropriately rubbing the facing in the presence of water and/or steam. In one embodiment of the invention, the felting operation is accomplished in an apparatus which comprises a pair of members having relative movement therebetween, as for 75 example, a stationary plate and an oscillating

plate. The shoulder pad blank is disposed between these two plates and subjected to the rubbing action thereof until the material has been felted. The members of the felting apparatus may be of a form corresponding to that of the shaped blank.

5 Instead of forming the filler into its desired shape and disposing it between the layers of material containing fibers having felting characteristics, another embodiment of the invention 10 comprises producing the shoulder pad blank in readiness for the felting operation in the apparatus employed for the making of the filler. In this embodiment, the fibers having the felting characteristics are showered under air pressure or 15 suction onto the rotating foraminous support until the desired thickness thereof has been built up. Then the fibers which are to form the filler are showered onto the already formed layer of feltable fibers. When the filler has reached the 20 desired dimensions, further showering thereof is discontinued and the fibers having felting characteristics showered onto said filler. When the 25 desired thickness of the feltable fibers has been secured, the blank is removed from the showering apparatus, which, incidentally, is of the type disclosed in applications Serial Nos. 66,208 and 170,008, and, after removing the entrapped air, is subjected to the felting operation.

30 The procedure described in the preceding paragraph may be employed if the filler is also formed of fibers having the felting characteristics.

35 Now referring to the drawing wherein several 40 illustrative embodiments of the invention are shown and wherein like reference numerals designate like parts, the reference numeral 1 designates a shoulder pad blank produced in accordance with this invention and provided with oppositely disposed V-shaped notches 2 in the edge thereof. The shoulder pad blank 1 is so constructed that when it is cut transversely thereof along the line 3 there will be obtained two complimentary shoulder pads, one of which is illustrated in Figure 3 and designated by the reference numeral 4.

45 In one form of the invention, to produce the shoulder pad blank 1, the filler 5 formed of the selected fiber, for example, cotton, is formed or 50 shaped into the predetermined contour, as above described. Discs 6 and 7 of a loose bat containing fibers having the felting characteristic are disposed on the top and bottom of the shaped filler. It is to be noted that each of the discs 6 and 7 extends beyond the thin edge 8 of the 55 filler 5. In other words, the marginal portion 9 of the disc 6 is superposed on and in contactual relationship with the marginal portion 10 of the disc 7. The assembly at this stage of the process, shown in Figure 2 of the drawing, is now subjected to a felting operation as hereinbefore described with the result that the fiber constituting the discs 6 and 7 is felted. The marginal portions 9 and 10 of the discs 6 and 7 are substantially integrally united by being felted together and provide the blank 1 with the marginal portion 11 which consists substantially of felted material. Due to the fact that the facings are 60 felted in situ on the filler, the surfaces of the final facings contacting with the surfaces of the shaped filler 5 are more or less felted together at 70 the zone of contact thereof.

65 Though for purposes of illustration the pad blank 1 has been shown as substantially heart-shaped, it is obvious that it may be circular, diamond-like, pear-shaped or of any shape to suit 75

the requirements of the various clothing manufacturers. Similarly, the dimensions of the pad blank 1 and hence the pad 4 may be such as is desired by the trade.

5 As is clearly shown in Figure 2, the filler 5 is relatively thick at its central zone and gradually tapers off therefrom in all directions to the relatively thin peripheral edge 8 and this shape of the filler 5 is substantially retained in the final product. The facings of the final product do not materially change the general contour of the fillers.

10 It is to be noted that the facings formed from the discs 6 and 7 completely envelope the filler 5 and follow generally the contour thereof. By virtue of the fact that the marginal portions 9 and 10 are felted together, the top and bottom facings may be said to be substantially continuous.

15 20 In some cases it may be desirable to provide the pad with a stiffener. When this is desired, a piece of any suitable stiffening material, such as, for example, buckram 12, (see Figure 4) is incorporated in the filler 5 during the production thereof.

25 As previously explained, the filler 5, instead of being made of cotton or wool, may be formed of a material containing fibers having the felting characteristic. Such an embodiment of the invention is illustrated in Figure 5 of the drawing. In this embodiment of the invention, it is to be noted that the facings 6' and 7' have been felted and that the marginal portion 11' consists of a substantially unitary structure. If desired, the 30 felting operation may be contained so that the product is felted throughout.

35 The shoulder pad 4, resulting when the shoulder pad blank 1 is cut along the line 3, has a relatively thick zone 13 along the cut edge and gradually tapers off therefrom to thin marginal portion 14 thereof which is the same as the marginal portion 11 of the blank 1. The facings 15 and 16, except for being severed at the cut edge of the pad 4, are substantially the same as the facings formed from the discs 6 and 7. Due to the marginal portion 14, the facings 15 and 16 may be said to be formed of substantially 40 one piece of felt.

45 The pad 4 shown in Figure 3 has a substantially flat bottom and a convex (arched) top. The invention is not restricted to such a shape and contour. The pad 4 may be formed so that it has substantially the form and shape that it has when sewed into a coat. This can be secured by 50 forming the pad blank 1 so that after severance the desired shaped pad may be secured or by appropriately forming the pad 4 after the production thereof.

55 Irrespective of the form and shape of the pad 4, the top and bottom surfaces thereof are formed of felt and the pad possesses the desired flexibility and resiliency as to lend itself for easy incorporation in a coat. It can be stitched very readily and requires no special precautions when being sewed into place in a coat. It is free from 60 stitches and no means other than those herein described are necessary to maintain the component parts thereof together.

65 Since it is obvious that various changes and modifications may be made in the above description without departing from the nature or spirit thereof, this invention is not restricted thereto except as set forth in the appended claims.

We claim:

70 75 1. A shoulder pad blank comprising a filler

having a thick central portion and tapering off therefrom to a relatively thin peripheral edge, and a facing formed of a felted material on both the top and bottom of said filler, each of said facings extending beyond and forming a marginal zone adjacent said thin edge, said facings being felted together in said marginal zone.

5 10 15 20 25 30 35 40 45 50 55 60 65 70 75 80 85 90 95

2. A shoulder pad comprising a filler relatively thick at a zone along one edge and tapering off gradually from the thick portion to a relatively thin edge, and a facing on both the top and bottom of said filler, said facings being formed of felted material and felted together adjacent the said thin edge.

3. A shoulder pad comprising a mass of fibers relatively thick at a zone along one edge and tapering off gradually from the thick portion to form a relatively thin edge, a felted material on the top of said mass and extending beyond said thin edge thereof, and a felted material on the bottom of said mass and extending beyond said thin edge thereof, said felted materials being substantially coextensive and felted together at the portions thereof extending beyond said thin edge.

4. A shoulder pad free of stitches comprising a mass of fibers relatively thick at a zone adjacent along one edge thereof and tapering off gradually from said thick portion to form a relatively thin edge, a facing on the top of said mass and extending beyond the thin edge thereof, a facing on the bottom of said mass and extending beyond the thin edge thereof, the extending portions of the said top and bottom facings being in superposed contactual relationship, said facings being felted in situ on said mass of fibers whereby the facings are felted to each other at the superposed contactual portions thereof.

5. In a method for making shoulder pads, the steps which comprise disposing a filler between two layers containing fibers having felting characteristics, said layers having their marginal zones in superposed contactual relationship, and felting said layers in situ to provide felted facings and whereby said marginal zones in superposed contactual relationship are felted together.

6. In a method for making shoulder pads, the steps which comprise disposing a filler between two layers containing fibers having felting characteristics, said layers having their marginal zones in superposed contactual relationship, felting said layers in situ to provide felted facings and whereby said marginal zones in superposed contactual relationship are felted together, and severing the resulting product transversely thereof to form a pair of complementary shoulder pads.

7. A shoulder pad blank comprising a filler and a substantially integral and continuous felted material enveloping said filler and constituting a facing therefor on both the top and bottom surfaces thereof, said filler being formed of a showered mass of fibers wherein the fibers extend in all directions and are interconnected with each other and wherein the fibers in the central zone are more densely compacted than those at the outer edge thereof and the density gradually decreases outwardly.

8. A shoulder pad blank having a facing formed of a felted material on both the top and bottom of said blank, said facings being felted together along the marginal zone adjacent the edge of said blank and a filler interposed between said facings, said filler being formed of a showered mass of fibers wherein the fibers extend in all directions and are interconnected with each other

and wherein the fibers in the central zone are more densely compacted than those at the outer edge thereof and the density gradually decreases outwardly.

5 9. A shoulder pad blank comprising a filler having a relatively thin peripheral edge, and a facing formed of a felted material on both the top and bottom of said filler, each of said facings extending beyond and forming a marginal zone adjacent said thin edge, said facings being felted together in said marginal zone, said filler being formed of a showered mass of fibers wherein the fibers extend in all directions and are interconnected with each other and wherein the fibers in the central zone are more densely compacted than those at the outer edge thereof and the density gradually decreases outwardly.

10 10. A shoulder pad comprising a filler relatively thick at a zone along one edge and tapering off gradually from the thick portion to a relatively thin edge, and a facing on both the top and bottom of said filler, said facings being formed of felted material and felted together adjacent the said thin edge, said filler being formed of a showered mass of fibers wherein the fibers extend in all directions and are interconnected with each other and wherein the fibers in the central zone are more densely compacted than those at the outer edge thereof and the density gradually decreases outwardly.

15 11. A shoulder pad comprising a mass of fibers relatively thick at a zone along one edge and tapering off gradually from the thick portion to form a relatively thin edge, a felted material on the top of said mass and extending beyond said thin edge thereof, and a felted material on the bottom of said mass and extending beyond said thin edge thereof, said felted materials being substantially coextensive and felted together at the portions thereof extending beyond said thin edge, said filler being formed of a showered mass of fibers wherein the fibers extend in all directions and are interconnected with each other and wherein the fibers in the central zone are more densely compacted than those at the outer edge thereof and the density gradually decreases outwardly.

20 12. A shoulder pad free of stitches comprising a mass of fibers relatively thick at a zone adjacent along one edge thereof and tapering off gradually from said thick portion to form a relatively thin edge, a facing on the top of said mass and extending beyond the thin edge thereof, a facing on the bottom of said mass and extending beyond the thin edge thereof, the extending portions of the said top and bottom facings being in superposed contactual relationship, said facings being felted in situ on said mass of fibers whereby the facings are felted to each other at the superposed contactual portions thereof, said filler being formed of a showered mass of fibers wherein the fibers extend in all directions and are interconnected with each other and wherein the fibers in the central zone are more densely compacted than those at the outer edge thereof and the density gradually decreases outwardly.

25 13. In a method for making shoulder pads, the steps which comprise showering fibers under air pressure upon a rotating foraminous support to produce a mass of fibers wherein the fibers extend in all directions and are interconnected and

wherein the fibers in the central zone are more densely compacted than those at the outer edge of the mass and the density gradually decreases outwardly, disposing said mass to constitute a filler between two layers containing fibers having felting characteristics, and felting said layers in situ on said filler to provide felted facings.

30 14. In a method for making shoulder pads, the steps which comprise showering fibers under air pressure upon a rotating foraminous support to produce a mass of fibers wherein the fibers extend in all directions and are interconnected and wherein the fibers in the central zone are more densely compacted than those at the outer edge of the mass and the density gradually decreases outwardly, disposing said mass to constitute a filler between two layers containing fibers having felting characteristics, said layers having their marginal zones in superposed contactual relationship, and felting said layers in situ to provide felted facings and whereby said marginal zones in superposed contactual relationship are felted together.

35 15. In a method for making shoulder pads, the steps which comprise showering fibers under air pressure upon a rotating foraminous support to produce a mass of fibers wherein the fibers extend in all directions and are interconnected and wherein the fibers in the central zone are more densely compacted than those at the outer edge of the mass and the density gradually decreases outwardly, disposing said mass to constitute a filler between two layers containing fibers having felting characteristics, felting said layers in situ on said filler to provide felted facings, and severing the resulting product transversely thereof to form a pair of complementary shoulder pads.

40 16. In a method for making shoulder pads, the steps which comprise showering fibers under air pressure upon a rotating foraminous support to produce a mass of fibers wherein the fibers extend in all directions and are interconnected and wherein the fibers in the central zone are more densely compacted than those at the outer edge of the mass and the density gradually decreases outwardly, disposing said mass to constitute a filler between two layers containing fibers having felting characteristics, said layers having their marginal zones in superposed contactual relationship, felting said layers in situ to provide felted facings and whereby said marginal zones in superposed contactual relationship are felted together, and severing the resulting product transversely thereof to form a pair of complementary shoulder pads.

45 17. A method of making shoulder pad blanks which comprises showering feltable fibers suspended in air on to a rotating foraminous support until the desired thickness has been built up, showering fibers to constitute the filler and suspended in air on to said built up rotating mass of feltable fibers until the desired thickness has been built up, showering feltable fibers suspended in air on the resulting built up rotating mass until the desired thickness has been secured, and subjecting the thus produced mass to a felting operation whereby the feltable fibers are felted together.
